OPERATING MEANS

Filed Feb. 6, 1926

UNITED STATES PATENT OFFICE.

ALBERT H. STEBBINS, OF LOS ANGELES, CALIFORNIA.

OPERATING MEANS.

Application filed February 6, 1926. Serial No. 86,465.

This invention relates to means for imparting a progressive vibratory movement to frames and other devices supported to be vibrated.

5 Various devices such as screens, concentrator tables and other forms of separators employ a progressive vibratory movement in effecting the separation of materials.

In some devices a strong progressive 10 movement is required to advance the materials being treated, while in other devices the travel of the materials may be produced largely through the action of gravity, in which case a relatively slight progressive 15 movement may be sufficient to effect the desired result. Still other devices may require a strong vibratory movement that will shake the materials being treated back and forth with considerable force, but with 20 a movement that is only slightly more energetic in one direction than the other, to advance the materials at a moderate rate of speed.

Having the above operating conditions 25 in mind, the present invention relates to an extremely simple construction for shaking the device to be operated back and forth with a moderate progressive movement.

One important feature of the present invention resides in an operating eccentric 30 having cables associated therewith so that as either cable is tensioned the other cable is slackened off, and in spring means connected to one of the cables for producing the progressive movement.

Another feature of the invention resides 35 in an unbalanced weight associated with the operating means so that it effects the tensioning of one cable more quickly than the other to thereby produce a progressive movement.

Other features of the invention and novel combination of parts in addition to the above will be hereinafter described in connection with the accompanying drawings 40 which illustrate one good practical form of the invention.

In the drawings—

Fig. 1 is a plan view of a supporting casing, having cable operating means constructed in accordance with the present invention, the frame that is supported for vibratory movement being indicated in dot-and-dash lines.

55 Fig. 2 is a side elevation of the device of

Fig. 1, the vibratory frame being shown in full lines; and

Fig. 3 is a diagrammatic view of a slightly modified construction of the operating cable, the sheaves associated with the cable being 60 shown in skeleton lines.

The operating means forming the subject matter of the present invention may be employed to operate concentrated decks, screens and various other devices requiring a progressive vibratory movement. The frame 10 which is mounted for vibratory movement may serve as the supporting means for a concentrator deck, screen, or such other device as it is desired to vibrate.

Any desired means may be provided to support the frame 10 for vibratory movement, and in the construction shown the supporting casing is provided with the uprights 11 to which the horizontally extending side 70 rails 12 are secured.

Various means might be provided for supporting the frame 10 for back and forth movement, and one simple construction to this end consists of the balls or rollers 13 80 which lie in trough-shaped bearing brackets 14 secured to the supporting casing, and the upper portion of these balls or rollers may extend into bearing brackets 15 secured to the under face of the frame 10. 85 The construction of the bearing brackets 14 and 15 is preferably such that they will guide the frame 10 in its back and forth movement.

The construction so far described forms no 90 essential part of the present invention, but is illustrated to make clear the construction and operation of the novel operating means which will now be described. This operating means is so constructed that one cable 35 is provided to pull the frame 10 in one direction while a second cable serves to pull the frame 10 in the opposite direction, and these cables are actuated by an eccentric which serves to let off one cable while it tensions the other.

In the construction shown in Figs. 1 and 2 a cable 16 is provided to pull the frame 10 in the left-hand direction and this cable has one end secured to the frame 10 by any 105 suitable means such as a rod or pin 17 secured to the under portion of the frame and about which the end portion of the cable is looped, the loop being formed by bending the end portion of the cable back against the 110

cable and securing it in place by a clamp 18. The portion of the cable extending from the frame 10 passes around a grooved sheave 19 mounted upon the shaft 20 the opposite ends of which shaft are supported by the brackets 21 mounted upon the supporting casing. The cable 16 passes from the grooved sheave 19 to the operating sheave 22 about which it is bent, and the other end of this cable is anchored to the supporting casing by any suitable means such as the adjustable bolt 23 provided with the nut 24, which secures the bolt to a transversely extending beam 25 of the supporting casing.

25 A similar cable 26 serves to pull the frame 10 in the right-hand direction and one end of this cable may be secured to the frame 10, in the manner above described, by looping the end portion about a pin or rod 17 secured to the under portion of the frame. The portion of the cable 26 extending from the frame 10 is looped about a second grooved sheave 19 supported for rotative movement and spaced lengthwise of the supporting casing with respect to the first mentioned sheave 19, and the cable 26 extends from the lower side of the sheave 19 around the opposite side of the operating sheave 22. The end of this cable is secured to the supporting casing by yielding anchoring means such as the coiled spring 27 mounted upon a bolt 28 attached to the end of the cable 26. The coiled spring may be confined between adjustable nuts 29 upon this bolt and a cross beam 30 secured to the supporting casing.

35 The operating sheave 22 is preferably provided with two cable receiving grooves disposed in spaced relation to each other, and extending entirely around the sheave, one groove being adapted to receive the cable 16 and the other the cable 26. This sheave is mounted upon the eccentric 31 which is secured to or formed integral with the operating shaft 32. The shaft 32 is rotatably supported by the bearing brackets 33 secured to the supporting casing and the shaft may be driven by the pulley 34. The construction of the eccentric and sheave 22 is such that the eccentric is free to rotate in this sheave to move the sheave bodily without rotating it, and this movement of the sheave 22 serves to tension one cable and slack off the other, as will be apparent from Fig. 2, wherein the sheave 22 is shown in full lines in the position it occupies when the frame 10 is at the left-hand end of its stroke, and the parts are shown in dotted lines in the position they occupy when the frame 10 is at the right-hand end of its stroke.

60 From the construction described it will be seen that as the operating shaft 32 rotates, the cables 16 and 26 are actuated to pull the frame 10 back and forth, but it should be noted that since the lower end of the cable 16 is non-yieldingly anchored to the support-

ing casing, while the lower end of the cable 26 is yieldingly secured to the supporting casing, the two cables will operate differently upon the frame 10. That is, the yielding anchoring means for the cable 26 will cause it to exert a continuous pull upon the frame 10 urging the same in a right-hand direction, whereas the non-yielding anchoring means for the cable 16 will cause this cable to exert a pull upon the frame 10 in the left-hand direction only when this cable is being tensioned by the operating sheave 22.

As a result of the construction just described, the constant pull exerted upon the cable 26 by the spring 27 tends to move the frame 10 more energetically in the right-hand direction than it does in the left-hand direction, thus imparting a progressive vibratory movement to the frame 10 in the right-hand direction. This progressive movement may be increased or decreased as desired by varying the strength of the spring 27, which may be done by adjusting the nuts 29 threaded upon the anchoring bolt 28.

It will be apparent that the operating cables 16 and 26 may constitute separate and distinct cables, as shown in Figs. 1 and 2, or may constitute a single cable, as shown in Fig. 3, wherein the upper stretch of the cable is rigidly secured to the under face of the frame 10 by the clamping means 35. In this construction the portion of the cable extending between the clamping means 35, and which is designated by 36, serves merely to transmit the pull directly from one operating portion of the cable to the other, and it will be apparent that the operation of the active portion 16 and 26 of the cables will be the same, whether they constitute separate and distinct cables, as in Figs. 1 and 2, or are connected by the portion 36, as in Fig. 3.

In some cases it may be desirable to provide means for supplementing the progressive vibratory movement produced by the yielding anchor 27 and this may be accomplished by providing the operating means for rotating the eccentric 31 with an unbalanced weight such as the weight 37 which may be fastened to the fly wheel or pulley 34, the arrangement being such that if the pulley is rotated in the direction of the arrow shown in Fig. 2, the action of gravity upon the weight 37 will tend to slow down the action of the eccentric 31 as the latter moves to the full line position of Fig. 2, and this weight will tend to speed up the action of the eccentric 31 as it approaches the dotted line position of Fig. 2. The effect of this will be to tension the cable 26 more quickly than the cable 16 to thereby pull the frame 10 more quickly in a right-hand direction than in the left-hand direction. The arrangement is such that both the spring 27 and weight 37 act to speed up the movement 130

of the frame 10 in a right-hand direction, and to retard somewhat the movement of this frame in the opposite direction, to thereby impart the desired progressive movement 5 to the frame 10 in the right-hand direction.

The operating means described forms an extremely simple construction for vibrating a frame as energetically as desired, and the nature of the progressive movement imparted to the frame may be varied by varying the strength of the yielding anchor secured to one of the cables.

Since the cables 16 and 26 perform separate and independent functions irrespective 15 of whether they are constructed as separate cables (as in Fig. 2) or as an integral cable (as in Fig. 3), the plural term "cables" has been used in the specification and claims as descriptive of both constructions.

20 What is claimed is:—

1. In combination with a frame supported for vibratory movement, operating means for the frame, comprising an eccentric shaft, a sheave mounted upon the eccentric, a cable extending around one side of the sheave and having one end anchored and its other end secured to the vibratory frame, a second cable extending around the opposite side of the sheave and having one end secured to the vibratory frame and a yielding anchor for its other end, and means for rotating the eccentric within the sheave to move the frame back and forth by alternately tensioning and slackening off the cables while the yielding anchor exerts a pull upon its cable that imparts a progressive vibratory movement to the frame.

2. In combination with a frame supported for vibratory movement, operating means 40 for the frame, comprising an eccentric shaft, a sheave mounted upon the eccentric, a pair of cables secured to the frame and extending therefrom about opposite sides of the sheave, a non-yielding anchor for the end of one cable, a resilient anchor for the end of the other cable, and means for rotating the eccentric to move the sheave so that it will pull the frame back and forth by alternately tensioning and slackening off the cables while the resilient anchor exerts a continuous pull upon its cable to move the frame more energetically in one direction than the other.

3. In combination with a casing having a frame mounted thereupon for vibratory movement, operating means for the frame comprising, an eccentric shaft, a sheave mounted upon the eccentric to be actuated thereby, cables each having an intermediate portion resting against the sheave and extending therefrom in opposite directions, means for securing an end of each cable to the frame, means for anchoring the other end of one of the cables to the casing, spring means for yieldingly securing the end of the

other cable to the casing, and means for operating the eccentric to move the sheave so that it alternately tensions and slacks off the cables to vibrate the frame while the spring acting through one cable moves the 70 frame more energetically in one direction than the other.

4. In combination with a frame supported for vibratory movement, operating means for the frame comprising, an eccentric 75 shaft, a sheave mounted upon the eccentric shaft to be actuated thereby, cables each having an intermediate portion resting against the sheave and extending therefrom in opposite directions and each cable having 80 one end anchored and its other end secured to the frame, means for rotating the eccentric to actuate the sheave so that it alternately pulls and slacks off the cables, and an unbalanced weight associated with the 85 rotating means to increase the speed of the eccentric through part of its rotation and decrease its speed during a different part of its rotation to thereby impart a progressive movement to the frame.

5. In combination with a frame supported for vibratory movement, operating means for the frame comprising, an eccentric shaft, a sheave mounted upon the eccentric shaft to be actuated thereby, a cable extending around one side of the sheave and having one end secured to the frame and its other end anchored, a second cable extending around the other side of the cable and having one end secured to the frame and its other end anchored, means for rotating the eccentric to actuate the sheave so that it alternately tensions and slacks off the cables, and an unbalanced weight associated with the rotating means so that the action 95 of gravity upon the weight will cause the sheave to tension one cable more quickly than the other.

6. In combination with a frame supported for vibratory movement, operating 100 means for the frame comprising, an eccentric shaft, a sheave mounted upon the eccentric shaft to be actuated thereby, a cable extending around one side of the sheave, a second cable extending around the other side 105 of the sheave, means for securing one end of each cable to the frame and for anchoring the other end of each cable, means for rotating the eccentric to actuate the sheave so that it alternately tensions and slacks off the 110 cables, an unbalanced weight associated with the rotating means to cause the eccentric to tension one cable more quickly than the other, and spring means arranged to supplement the action of the weight in imparting a progressive movement to the frame.

In testimony whereof, I have signed my name to this specification.

ALBERT H. STEBBINS.
